UNITED STATES PATENT OFFICE

168,334

AUXILIARY CHILD'S SEAT OR THE LIKE

Emil A. Contadino, Cincinnati, Ohio

Application August 16, 1952, Serial No. 21,071

Term of patent 14 years

(Cl. D15—1)

To all whom it may concern:

Be it known that I, Emil A. Contadino, a citizen of the United States, residing at Cincinnati, county of Hamilton and State of Ohio, have invented a new, original, and ornamental Design for an Auxiliary Child's Seat or the like, of which the following is a specification, reference being had to the accompanying drawings, forming part thereof:

Fig. 1 is a perspective view of an auxiliary child's seat showing my new design.

Fig. 2 is a side elevational view of the device of Fig. 1.

Fig. 3 is a rear elevational view of the device of Fig. 1.

Fig. 4 is a top plan view of the device of Fig. 1.

I claim:

The ornamental design for an auxiliary child's seat or the like, as shown.

EMIL A. CONTADINO.
